UNITED STATES PATENT OFFICE.

GEORGE H. A. ROEHRIG, OF SHERIDAN, PENNSYLVANIA.

DISPLAY-PACKAGE.

No. 903,005.

Specification of Letters Patent.

Patented Nov. 3, 1908.

Application filed November 6, 1906. Serial No. 342,221.

To all whom it may concern:

Be it known that I, GEORGE H. A. ROEHRIG, citizen of the United States of America, residing at Sheridan, in the county of Allegheny and State of Pennsylvania, have invented certain new and useful Improvements in Display-Packages, of which the following is a specification, reference being had thereto to the accompanying drawing.

10 This invention relates to packages, and more particularly to packages for cakes, crackers, and similar eatables, the package being designed for display purposes and for preserving and maintaining crackers and 15 cakes in a crisp and fresh condition. To this end, I have devised a novel display package wherein positive and reliable means are employed for effecting an hermetically sealed inclosure for crackers and cakes, which can 20 be observed or viewed at any desired time.

My package is constructed of durable material and is provided with a sight opening covered with a transparent material, said material being sealed to the package, where- 25 by the interior of the same will be maintained in a dry state and free from atmospheric conditions that may surround the same.

The detail construction of my improved 30 package will be presently described and then specifically pointed out in the appended claims, and referring to the drawing forming part of this specification, like numerals of reference designate corresponding parts 35 throughout the several views, in which:—

Figure 1 is a perspective view of the package, Fig. 2 is a front elevation of the same, Fig. 3 is a cross sectional view, and Fig. 4 is an enlarged perspective view of a portion 40 of the package illustrating the manner of securing the transparent material over the sight opening of the package.

My improved package is preferably constructed of paste board, card board, paper 45 and a transparent material such as mica or celluloid. The package is preferably made into an oblong shape whereby a plurality of crackers and cakes can be conveniently stored in the same. The body of the package 50 is made of a piece of paste board which forms the bottom 1 of the package, side walls 2 and 3, end flaps 4, and a lid 5. The interior of the box contains a lining of paraffin paper, while the exterior of the box is sealed by an 55 outer covering 7 that is broken when the box is opened. The inner lining and the outer

covering of the package form an air tight compartment for cakes or crackers 8.

My invention resides in providing one of the sides of the box with a sight opening 9, 60 said opening being formed by cutting away the paste board forming the side of the box and the inner lining and outer covering. The sight opening 9 is then closed by a transparent piece of material 10 as mica or celluloid. The edges of the transparent piece of material are secured to the inner edges of the package bordering upon the opening 9 by cement 11 or a similar adhesive material, the cement besides holding the transparent piece 65 of material extends upon the bottom 1 and the lid 5 to further insure positive connection between the transparent piece of material 10 and the side of the box. The cement may also serve to hold the inner lining in position 70 within the package.

From the foregoing it will be observed that I have devised a novel display package that can be hermetically sealed to preserve the contents of said package, and at the same 80 time permit of the contents being viewed.

I do not care to confine myself to the shape or material used in connection with the package, and such changes in the arrangement of the transparent material and other details of 85 construction as are permissible by the appended claims, may be resorted to without departing from the spirit and scope of the invention.

What I claim and desire to secure by Letters Patent, is:—

1. A package or carton for crackers and the like, comprising a foldable box body having an opening in one of its walls, an inner air-proof lining and an outer air-proof wrapper 95 for said box, said lining and wrapper each having an opening corresponding in size and position to the opening in the box body, and a transparent covering for said openings, said covering being of a size greater than 100 that of the openings, and interposed between the lining and the box body, said covering being hermetically sealed to said lining, the seal extending beyond the periphery of said covering and forming the sole connection of 105 the lining and box-body.

2. A package or carton for crackers and the like, comprising a foldable box body having one of its walls formed with an opening, an air-proof lining for said box, said lining 110 having an opening corresponding in size and position with the opening in the body,

- and a transparent covering for said openings interposed between the body and lining, said covering being of a size to project beyond the edges of the openings, said covering and lining being adhesively connected along the projecting portions of the covering, the adhesive extending beyond the edges of the covering and forming a positive connection for the lining and body beyond and adjacent to the periphery of the covering, the remaining portion of the lining being free from adhesive connection with the box-body.
3. A package or carton for crackers and the like, comprising a body of pasteboard or like material embodying side-walls, a bottom, a top, and end flaps, an interior air-proof lining, and an exterior air-proof wrapper or covering, one of said side-walls having an opening, and a transparent covering for said opening adhesively secured to said air-proof lining and contacting with the inner face of said wall, the adhesive forming a positive connection between the lining and the walls of the box beyond the periphery of the transparent covering, said transparent covering being substantially co-extensive with the side-wall with which it contacts, the adhesive connection of the lining and box-body extending partially over the adjacent end-walls of the box, the remaining portion of the lining being free from adhesive connection with the box-body.
- 10 to the periphery of the covering, the remaining portion of the lining being free from adhesive connection with the box-body.
- 15 3. A package or carton for crackers and the like, comprising a body of pasteboard or like material embodying side-walls, a bottom, a top, and end flaps, an interior air-proof lining, and an exterior air-proof wrapper or covering, one of said side-walls having an opening, and a transparent covering
